UNITED STATES PATENT OFFICE.

WILLIAM E. BURKS, OF ASHLAND, KENTUCKY, ASSIGNOR OF ONE-HALF TO V. V. ADKINS, OF ASHLAND, KENTUCKY.

COMBINED HOLDER FOR PAPER SACKS AND ROLL-PAPER.

No. 873,409.

Specification of Letters Patent.

Patented Dec. 10, 1907.

Application filed December 28, 1906. Serial No. 349,866.

To all whom it may concern:

Be it known that I, WILLIAM E. BURKS, citizen of the United States, residing at Ashland, in the county of Boyd and State of Kentucky, have invented certain new and useful Improvements in Combined Holders for Paper Sacks and Roll-Paper, of which the following is a specification.

This invention relates to store service apparatus and more particularly to a support for paper sacks.

The support for paper sacks embodies a rack containing shelves upon which the bundles of paper sacks are placed, guards to prevent displacement of the sacks, and means for holding the sacks upon the shelves, the guards being of novel formation and having detachable connection with the shelves to admit of the bundles of sacks being conveniently placed in position.

For a full description of the invention and the merits thereof and also to acquire a knowledge of the details of construction and the means for effecting the result, reference is to be had to the following description and accompanying drawings, in which:

Figure 1 is a front view of the device. Fig. 2 is a detail perspective view of a portion of the rack for receiving the paper sacks. Fig. 3 is a side view of the appliance.

Corresponding and like parts are referred to in the following description and indicated in all the views of the drawings by the same reference characters.

The device comprises a rack and a holder, the latter adapted for roll paper and the former for receiving paper sacks of graduated sizes. Both the rack and the holder form parts of a single structure and are mounted upon a single base which in the present instance comprises bars 1. The rack is mounted upon one portion of the base and the holder upon the end portion of said base opposite to that receiving the rack.

The rack comprises four uprights 2, the same being upwardly converged, and shelves 3, the latter being located at different elevations and gradually decreasing in size from bottom to top to accommodate the different standard sizes of paper sacks. A guard 4 is provided at each end of the shelves and is detachably connected thereto so as to be removed when it is required to place a bundle of paper sacks upon any shelf. The guards 4 limit outward movement of the piles of sacks,

while at the same time permitting the sacks to be removed from the shelves one at a time. The guards are of like construction, hence a detailed description of one will suffice for a clear understanding thereof. Each guard is preferably constructed of wire of suitable gage, the wire blank being doubled upon itself and bent to provide the eye 5, spring coil 6, uprights 7, coils 8, horizontal bars 9 and journals 10. The uprights 7 are arranged preferably at an obtuse angle to the horizontal bars 9 and are adapted to engage with the outer ends of the paper sacks and hold the same in convenient position to admit of each being detached one at a time. The eye 5 projects inwardly and overlaps the pile of sacks, thereby preventing the same from getting beyond control of the protectors.

The spring coil 6 admits of the uprights 7 being pressed together at their lower ends when it is required to disconnect the journals 10 from the shelves, or to press the same inward when placing the protectors in position. The spring coils 8 provide for a yielding or spring movement of the upright portion of the protector, thereby facilitating the removal of the topmost sack of a pile. Each shelf is provided at opposite ends with a notch 11 and the bottom side of said notch is closed by means of a plate 12, the latter forming a rest to hold the protector in proper position, the horizontal bars 9 of the protector resting thereon.

Openings 13 are formed in the vertical side walls of the notches 11 near the inner ends thereof to receive the journals 10, said openings being provided preferably by notches cut into the lower side of the shelves and which notches are closed by the plate 12 which also closes the lower side of the notch 11 in the manner stated. The notches 11 receive the horizontal bars of the protectors and at the same time provide convenient means for admitting of the sacks being grasped when placed in position, or when it may be required to remove the same from the shelves. When any shelf is empty, the protectors at the ends thereof may be turned upward out of the way without necessitating their removal and endangering their loss or misplacement so as not to be conveniently at hand when required for use. By having the shelves provided at opposite ends with protectors, the paper sacks may be drawn from

either end thereof as may be found most convenient. The shelves are of a length to receive the bundles of sacks as received from the factory. The sacks when in original packages, have their ends overlapped so as to form uniform packages which would not be the case, if arranged in piles one upon the other because of the increased thickness of the end corresponding to the bottoms of the 10 sacks. It will thus be understood that the shelves are enabled to receive about twice the number of sacks which they would otherwise hold if no provision were made for the overlapping of the end portions of the sacks in 15 the original packages.

Pressure bars, or plates 14, coöperate with the shelves and are centrally disposed and are adapted to exert and confine pressure upon the inner overlapped ends of the sacks 20 to prevent displacement thereof without interfering with the removal of the individual sacks when pulled upon after being disconnected from the protectors. The pressure bars, or plates 14, operate by gravity and are mounted upon upright rods, or bars 15, which are stapled, or otherwise attached, to the top 25 portions of the shelves 3. Slots, or openings 16, are formed in opposite ends of the pressure bars 14 to receive the rods, or bars 15. 30 The twine holder 17 is placed upon the top of the rack and may be of any construction and design. A rod, or bar 18, is secured to the side of the rack and is provided at its upper end with a guide 19 through which the 35 twine 20 passes, a link 21 being mounted upon the rod, or bar 18, to move freely thereon and having the twine 20 pass therethrough. When drawing the twine 20 from the holder, the link 21 moves upward upon 40 the rod, or bar 18 and after the length of twine drawn from the holder is cut, or broken, the link 21 descends upon the rod, or bar 18, and takes up the loose end of the twine.

The holder for the roll paper comprises 45 superposed frames of similar formation, each comprising uprights 22 and a horizontal, or cross bar 23, connecting the respective uprights. A shoulder 24 is provided upon the inner side of each upright 22 and is notched 50 in its upper end to receive the end of a roller 25 upon which the roll 26 of wrapping paper is mounted. The paper comprising the roll is usually wound upon a hollow center in which end pieces 27 are fitted, said end 55 pieces having openings to receive the roller 25. This construction admits of any length of roll paper being mounted upon the roller 25 provided said roll paper does not exceed the length of the roller 25. To prevent 60 movement, or endwise play, of the roll paper upon the roller 25 when of less width than the distance between the shoulders 24, or the uprights 22, a gage 28 is provided, the same consisting of an arm having an opening 29 65 through which the roller 25 passes, said arm

having its lower end bent as shown at 30 and rebent as indicated at 31, a rod, or bar 32, passing through openings 33 formed in the vertical portion 31 and the lower end of the gage 28. The gage 28 is preferably formed 70 of a strip of metal so as to yield and its upper end is slightly inclined away from the adjacent end of the roll paper so as not to come in injurious contact therewith. An off-set 75 34 is provided in the lower portion of the gage to throw the upper and lower ends in different vertical planes, with the result that a portion of the gage only, viz: the part adjacent to the roller 25 comes in contact with the central portion of the roll paper. The 80 construction is such as to admit of the gage 28 being moved to any position in the length of the roller 25 to adapt the same to the length of the roll paper mounted thereon. By having the foot of the gage bent and rebent as shown at 30 and 31, and the rod, or bar 32, passed through openings 33, the gage 85 automatically locks itself upon the rod, or bar 32. The frame of the holder is provided with the usual pressure bar and cutter 35 90 which is spring actuated and mounted in bearings applied to the horizontal, or cross bar 23. The rod, or bar 32, is supported at its ends in openings formed in the uprights 22 and may be of any line in cross section. 95 A brace 36 connects the upper ends of the rack and holder.

Having thus described the invention, what is claimed as new is:

1. A store service apparatus of the character described, consisting of a base, uprights supported on said base, a shelf secured to the uprights and adapted to receive piles of paper sacks, protectors secured to both ends of the shelf and each consisting of a horizontally extending portion attached to the shelf and extending outwardly therefrom and an upwardly extending portion adapted to support the sacks at their outer ends, upright rods secured to the shelf at opposite sides 100 thereof and at the middle of the shelf, and a gravity actuated pressure bar slotted at its ends, the upright rods extending through the slots and the bar being adapted to rest upon the piles of sacks upon the shelf. 105

2. In store service apparatus, the combination of a shelf and a protector coöperating therewith, the same comprising spaced upright and horizontal members, the latter having outer extensions to make detachable 110 connection with the shelf, coils at the junction of the upright and horizontal members and other coils at the top of the said uprights, one of the coils being in the plane thereof and the other coil about at a right angle to the 115 plane of the uprights to extend over a pile of paper sacks, or the like, placed upon the shelf and abutting against the said uprights. 120

3. In combination a shelf having a notch and openings in opposite walls of the notch 130

and a protector comprising upright and horizontal portions, the latter lying in the notch below the upper surface of the shelf and adapted to be pressed together and having 5 outer extensions to enter the said openings in the walls of the notch.

4. In combination, a shelf provided with a notch and having openings in opposite walls of the notch, a plate closing the bottom 10 side of the notch and a protector comprising upright and horizontal portions, the latter lying in the notch upon the said plate and adapted to be pressed together and having extensions to enter the openings in the vertical walls of said notch. 15

5. In combination, a shelf adapted to receive a pile of paper sacks arranged with their end portions overlapped, protectors at opposite ends of the shelf to prevent outward displacement of the pile and a pressure 20 bar arranged to exert a confining influence upon the overlapped portions of the said sacks.

In testimony whereof I affix my signature in presence of two witnesses.
